UNITED STATES PATENT OFFICE.

RAY A. McHALE, OF SYRACUSE, NEW YORK, ASSIGNOR TO LOIS T. McHALE, OF SYRACUSE, NEW YORK.

TIE BRACE FOR CONCRETE FORMS.

Application filed February 4, 1921. Serial No. 442,421.

To all whom it may concern:

Be it known that I, RAY A. McHALE, a citizen of the United States, and a resident of Syracuse, in the county of Onondaga and State of New York, have invented a certain new and useful Tie Brace for Concrete Forms, of which the following is a specification.

This invention has for its object a tie brace for holding the opposing walls of concrete forms in position or in parallelism to each other which tie brace is particularly simple and economical in construction, readily placed in position and in which all the parts thereof are readily removed from the wall so that none of the parts are left in the concrete wall.

The invention consists in the novel features and in the combinations and constructions hereinafter set forth and claimed.

In describing this invention, reference is had to the accompanying drawings in which like characters designate corresponding parts in all the views;

Figure 1 is an elevation, partly in section of this tie brace, the contiguous part or walls of the former being shown in section.

Figure 2 is a plan view of parts seen in Fig. 1.

Figure 3 is an enlarged fragmentary sectional view of one of the blocks, the contiguous portions of the tie rod and pull rod being also shown.

Figure 4 is an elevation looking to the right in Fig. 3.

This tie brace comprises generally, opposing blocks or sleeves designed to lie against the opposing faces of the walls of the form, a tie rod connecting the blocks, tension members having detachable connection with the blocks and extending through the walls of the form, and means for applying tension to said members.

1 designates the blocks; 2 the tie rod which threads into the opposing ends of the blocks as at 3.

Each of the blocks is also formed with an internal cavity 5 having an entrance opening in the form of a key slot 6 through the outer end of the block.

7 designates tension members which are preferably, pull rods, each of which is formed with a hook-shaped end 8 arranged to interlock in the cavity through the key slot by a relative endwise and turning move-

ment of the rod and the block. Each rod 7 and block 5 are provided with means for holding the pull rod from lateral displacement relatively to the block when the hook is interlocked in the cavity and out of alignment with the slot 6, that is, with means for preventing the rod moving radially in the slot 6, especially when the slot 6 extends downwardly.

As here illustrated, the inner face of the end wall 9 of the block 5 is formed conical or undercut as at 10 and the hook 8 is provided with a bevel surface 11 complementary to the conical surface 10. Hence, after the rod has been passed endwise to carry the hook 8 through the slot 6 and turned, the bevel face 11 of the hook hugs the conical or undercut face 10 and thus holds the rod from displacement until the rod is tightened.

Also, when the pull rod is being tightened these surfaces act inclined plane fashion on each other. Preferably, a shoulder 10^a is provided in the cavity of the block in position to limit the turning of the rod 7 when the hook 8 is diametrically opposite the slots 6. Also, as a precaution against the rod displacing laterally in the slot 6 before it is tightened in case the depth of the cavity of the block is enough greater than the thickness of the hook 8 from front to rear thereof the slot 6 is contracted near its inner end by inwardly projecting shoulders 6^a which extend part way around the rod 7 when the hook 8 has been passed through the slot, and the hook 8 is provided with grooves 8^a to clear such shoulders.

The end face of each block is also cupped out as at 12 so that the block engages the inner face of the form 13 at its edge 14 only and thus obtains an even bearing on the form 13. Also, the block may be provided on such end face with a lip 12^a for entering the hole 12^b in the form.

The means for drawing the tension rod 7 endwise and tightening it in order to draw the block against the inner face of the form, as here shown, comprises a wedge 15 inserted between a hook-shaped or looped end 16 of the rod and pressing against the outer face of the form as against a beam 17 through which the rod extends.

The pull rod 7 outside of the beveled hook and the wedge form the subject matter of my application, Sr. No. 434,988, filed January 4, 1921.

In operation, the blocks 1 are threaded on the ends of the rod 2 and thereafter the pull rods inserted through suitable openings in the beam 7 and wall 13 and interlocked 5 with the blocks 4. The wedges 15 are then placed in position.

After the concrete or cement is set the forms are removed by displacing the wedges unlocking the rods 7 in the blocks 1 and re- 10 moving them permitting the form 13 to be removed. One of the blocks 1 is then unscrewed and the tie rod knocked out.

Owing to the fact that the blocks thread on the tie rod, the tie rod can be removed in- 15 stead of being left in the wall.

What I claim is:

1. In a tie brace for concrete forms the combination of a pair of blocks, a tie rod connecting the blocks, each block being 20 formed with an internal cavity and with a radial slot in its end wall, the slot opening into the cavity, and tension rods arranged substantially in alinement with the tie rod, each tension rod having a hook at its inner 25 end arranged to pass through the slot into the cavity and interlock with the end wall thereof upon successive endwise and partial rotary movements of the tension rod, substantially as and for the purpose described.
2. In a tie brace for concrete forms, the combination of a pair of blocks, a tie rod to the ends of which the blocks are secured each block being formed with a cavity, and a key slot opening into the cavity through 30 35 the outer end of the block, the wall of the cavity around the key slot being conoidal or beveled, and tension members arranged substantially in alinement with the ends of the tie rod and having hooks at their ends, the 40 hooks having backwardly inclined faces for conforming to the cone of the wall of the

cavity and interlocking therewith when the hook is turned in the cavity out of alinement with the slot, substantially as and for the purpose set forth.

3. In a tie brace for concrete forms, the combination of a pair of blocks, a tie rod connecting the blocks, each block being formed with a cavity and with a key slot at the outer end of the cavity, tension rods arranged substantially in alinement with the ends of the tie rod and each having a hook at its end arranged to interlock in the cavity of the adjacent block through the key slots by relative endwise and rotary movements of the rod and the blocks, and means for holding the rods from lateral displacement in the slot when the hook is interlocked in the cavity, substantially as and for the purpose described.

4. In a tie brace for concrete forms, the combination of a pair of blocks, a tie rod connecting the blocks, each block being formed with a cavity and with a key slot at the outer end of the cavity, tension rods arranged substantially in alinement with the ends of the tie rod and each having a hook at its end arranged to interlock in the cavity of the adjacent block through the key slot by relative endwise and rotary movements of the rod and the blocks, the slot being provided with shoulders on opposite sides thereof and the rod at the base of the hook being provided with grooves for receiving the shoulders, substantially as and for the purpose set forth.

In testimony whereof, I have hereunto signed my name, at Syracuse, in the county of Onondaga, and State of New York, this 28th day of January, 1921.

RAY A. McHALE.
